UNITED STATES PATENT OFFICE.

WILLIAM I. GOODIN, OF CINCINNATI, OHIO.

NECKTIE-HOLDER.

SPECIFICATION forming part of Letters Patent No. 625,160, dated May 16, 1899.

Application filed April 4, 1898. Serial No. 676,364. (No model.)

To all whom it may concern:

Be it known that I, WILLIAM I. GOODIN, a citizen of the United States, residing at Cincinnati, in the county of Hamilton and State 5 of Ohio, have invented certain new and useful Improvements in Necktie-Holders; and I do hereby declare the following to be a full, clear, and exact description of the invention, reference being had to the annexed drawings, 10 which form a part of this specification.

My invention comprises a light, simple, and convenient holder which is capable of ready application to an ordinary neckband-button before a detachable collar is fastened thereto, 15 and then the upper edge of the necktie is engaged under a hooked portion or clasp of said holder, thereby preventing said tie working up and becoming exposed above a coat-collar, as hereinafter more fully described.

20 In the annexed drawings, Figure 1 is a rear elevation of my necktie-holder. Fig. 2 is a similar elevation, but showing said holder suspended from a neckband-button. Fig. 3 is a similar view, but showing a collar engaged with said button and the hooked portion of the holder turned up behind said collar. Fig. 4 is another rear elevation, but showing a necktie engaged under said hook or clasp.

30 A represents a small thin metallic plate, of any suitable size and shape, and B is a perforation in said plate, which hole permits the passage through it of the head of an ordinary neckband-button. Adapted to swing freely 35 from the loop a of this plate is a wire C, so bent as to form a hook or clasp, which normally hangs down from said plate and in a plane somewhat in front of it.

D in Fig. 2 is the rear portion of a neckband, and E is an ordinary button wherewith 40 the ends of said band are fastened together in the usual manner.

F in Fig. 3 is the rear portion of a detachable shirt-collar, and G is a hole in said collar for engagement with the button E. 45

H in Fig. 4 is the rear portion of any kind of a necktie.

From the above description it is evident that the plate A is first suspended from the button E and then the collar F is engaged with 50 said button. After this act hook C is swung up behind the collar, and the necktie H being then engaged under said hook or clasp it is evident said tie cannot work up and be exposed over a coat-collar. Again, as the holder 55 consists of a thin flat plate with a light wire coupled to it, there is no material projection to rub against the back of the wearer's neck, neither is there any danger of the device injuring the shirt-band, collar, or tie. Finally, 60 as the clasp proper, C, is a single piece of wire whose ends are bent and securely housed within the coupling-roll a at the lower edge of the perforated plate A B, it is evident the holder is entirely free from hooks, points, or 65 projections of any kind to engage with a necktie.

I claim as my invention—

The within-described specific construction of necktie-holder, which device includes the 70 attaching-plate A, provided with an eye B, to engage a collar-button, and having at its lower edge a loop a, having hinged within it the ends of a clasp C, made of a single piece of wire, the sides of said clasp being carried 75 down from said joint, then bent upwardly to form a hook, all as shown and set forth.

In testimony whereof I affix my signature in presence of two witnesses.

WILLIAM I. GOODIN.

Witnesses:

JAMES H. LAYMAN,
EARLE R. PASSEL.
